UNITED STATES PATENT OFFICE.

FRANK W. TAYLOR, OF ST. PAUL, MINNESOTA.

DESIGN FOR A COLLAR OR CUFF BUTTON.

SPECIFICATION forming part of Design No. 29,563, dated November 1, 1898.

Application filed October 4, 1898. Serial No. 692,646. Term of patent 14 years.

To all whom it may concern:

Be it known that I, FRANK W. TAYLOR, of St. Paul, in the county of Ramsey and State of Minnesota, have invented and produced a new and original Design for Collar or Cuff Buttons, of which the following is a specification, reference being had to the accompanying drawings, forming a part thereof, in which—

10 Figure 1 is a perspective view of a button embodying the features of my design, and Fig. 2 is a plan view of said button.

15 The shank A of the button has two opposing flat sides α and two opposing curved sides α' , which latter in cross-section appear segmental. The shank at one end appears as a part of a disk B, while at the opposite end the

shank seems to form a portion of the head C, the head being of a spherical shape. A bar D apparently passes through the head, and 20 the ends d of the bar are inclined outwardly from their upper surfaces in opposite directions.

The leading feature of the design consists in the head C and the bar D, appearing to pass 25 through the head, the ends of said bar being beveled.

I claim—

The design for collar and cuff buttons herein shown and described.

FRANK W. TAYLOR.
